A. D. SCHNACKENBERG, OF BROOKLYN, NEW YORK.

Letters Patent No. 75,582, dated March 17, 1868.

IMPROVED VESSELS FOR MINERAL-WATER.

The Schedule referred to in these Letters Patent and making part of the same.

TO ALL WHOM IT MAY CONCERN:

Be it known that I, A. D. SCHNACKENBERG, of Brooklyn, Kings county, New York, have invented a useful Improvement in Mineral-Water Jars and Bottles; and I do hereby declare that the following is a full, clear, and exact description thereof, which will enable others skilled in the art to make and use the same, reference being had to the accompanying drawing, forming a part of this specification.

The drawing represents a vertical sectional view of my invention.

This invention relates to a new manner of constructing the head or stopper of a mineral-water jar or bottle, of that class from which the liquid is discharged by the pressure of gas when a valve is opened; and the invention consists in arranging a straight pipe, through which the liquid is filled in and discharged, so that its outer end is higher than its lower end, and in combining it with a valve-stem in such a manner that the liquid can be filled in when the bottle is standing, and can be discharged by turning the bottle bottom up, and opening the valve. Thereby the use of the draught-tube generally used in mineral-water bottles is dispensed with, and the cost of the apparatus is considerably reduced.

A represents the neck of a glass or stone jar, made of sufficient strength and of suitable shape and size. Around this neck is fitted, in any suitable manner, a metal ring, B, having a screw-thread around its outside. C is a metal cap, screwed upon the ring B, thereby covering and closing the mouth of the bottle. This cap is perforated at or near its centre, and has a tubular extension, *a*, above the hole. Within the tube *a* is arranged a valve-stem, D, having a shoulder, *b*, and in the tube *a* is also a shoulder, *c*, as shown. Between the shoulders *b* and *c* is arranged, around the stem D, a spiral spring, E, by which the stem is drawn up, so that a rubber or other valve *d*, secured to the lower end of the stem, will be drawn against the under side of the cap-plate, and will thereby completely close the hole in the same.

By pressing upon a knob, *e*, formed on the upper outer end of the stem D, the valve *d* will be pushed down, and the hole in the cap will be opened. F is a short tube, soldered or otherwise secured to the cap C, so as to communicate with the hole through the cap. This tube F is straight, or nearly so, and extends from the cap upwards in a vertical or oblique direction. When the valve is opened, the liquid can be filled through the tube F, and can then be discharged by turning the bottle around, so that its bottom is up, and the cap down, and by then opening the valve it will flow out easily.

Heretofore draught-tubes had to be secured to the caps of mineral-water bottles or jars, said tubes reaching down nearly to the bottom of the bottle. Such bottles were filled by turning them around while they were emptied, while the bottle stood upright. The contents of such bottles had to be highly charged with gas, as otherwise the liquid could not be forced up through the entire length of the draught-tube.

By the use of my invention, the draught-tube is dispensed with, and thereby the expenses of the apparatus are reduced, and the bottle need not be charged so highly with the gas, as the natural weight of the liquid causes the same to be discharged when the bottle is turned around, and when the valve is opened. By requiring less gas, many accidents will be prevented, the excessive charge causing at present frequent explosions. The discharge-tubes of ordinary mineral-water bottles are hook-shaped, so that the liquid will flow downward when discharged from an upright bottle; thereby the filling of the bottle can only be performed by turning the bottle bottom up, which is very inconvenient for the charging process, which inconvenience is completely obviated by my invention.

I claim as new, and desire to secure by Letters Patent—

A cap, C, for mineral-water bottles or jars, when provided with a valve, *d*, and upright or nearly upright tube F, substantially as herein shown and described, so that the use of a draught-tube is dispensed with, as set forth.

A. D. SCHNACKENBERG.
